UNITED STATES PATENT OFFICE

CHARLES HERMAN PASCHKE, OF BUFFALO, NEW YORK, ASSIGNOR TO FREDERICK A. PASCHKE, OF SWEETWATER, IDAHO

FUEL BURNER

Application filed May 27, 1929, Serial No. 366,410. Renewed March 11, 1932.

This invention relates to improvements in gaseous fuel burners generally, and more particularly to a type of the same adapted for heating purposes in furnaces, radiators and the like.

An object of the invention is to provide a burner of the class set forth which will be comparatively simple and inexpensive to manufacture, extremely durable, efficient and economical in use, and convenient and easy to install and operate.

Another object of the invention is to provide a burner as hereinbefore characterized which employs certain features of construction and adjustment which permits of a maximum generation of heat with a minimum consumption of gaseous fuel and allows for a comparatively wide range of proportionment of the gaseous fuel and air and consequently of regulation of the amount of heat to be generated.

A further object of the invention is to provide a novel form of mixing device which functions to cause a most thorough commingling of the gaseous fuel and air throughout the range of proportionment and regulation of the same as aforesaid.

With the foregoing and other equally important objects and advantages in view, the invention resides in the certain new and useful combination, construction and arrangement of parts as will be hereinafter more fully described, set forth in the appended claims and illustrated in the accompanying drawing, in which:

Figure 1 is a side elevation of the burner in assembly with a main fuel mixing device;

Figure 2 is a perspective view of the parts of the burner per se in position for assembly;

Figure 3 is a vertical section through the burner parts, as illustrated in Figure 2, but after the assembly thereof has been made; and

Figure 4 is a vertical transverse section through a form of floor radiator or the like with the burner housed within the casing thereof.

Referring to the drawing, wherein like characters of reference designate corresponding parts throughout the several views there-

of, the embodiment of the invention, as illustrated therein by way of example, comprises a member or plate 10, which may be other than the circular or convex form shown if desired, but in any case, is made up of a fire 55 resistant material and has a tubular portion 11 depending centrally from the lower side thereof, and an opening 12 formed through the same in the plane of the vertical axis of the latter.

The member or plate 10 and the tubular portion 11 are preferably formed integrally, but will, if desired, be made separately, and, in the latter case and as shown, the portion 11 is cut away at its upper end to either side 65 of a pair of diametrically arranged attaching portions 13, which are to be brazed or welded to the member or plate 10, as at 14. When the parts 10 and 11 are in one piece, the latter part 11 will be similarly cut away 70 to either side of the integral portion 13, and, in either case, openings 12a so formed at these points will act to spread the flames radially outward of the under side of the member or plate 10. The portion 11 is further cut away, 75 as at 15, at the opposite sides of the same and at a slight distance from its lower end, to provide circumferentially elongated air intake ports arranged for cooperation with a pair of similarly formed ports 16, the latter being provided in a detachable extension or nipple 17, over which the portion 11 is slidably engaged, which extension or nipple rises from the upturned end of an L coupling 18.

As shown, the burner member or plate 10 and the tubular portion 11 are to be adjusted vertically of the extension or nipple 17 for the regulation of the size of the opening of the registering ports 15 and 16, by means of a pair of screws 19 threaded downwardly through suitable openings formed in the member or plate 10 for their reception. These screws 19 have their lower end portions engaged in apertured lugs 20 projecting inwardly from the attaching portions 15, of the tubular portion 11 and their extreme lower ends bearing against the upper end edge of the tubular extension or nipple 17. Thus, when the screws 19 are turned 100

in one direction, the member or plate 10 and the tubular portion 11 will be lowered, and contrariwise raised, when the screws 19 are turned in the reverse direction. When fully lowered, the portions 15 and 16 will be out of registry, and the intake of air therethrough from the surrounding atmosphere prevented.

The horizontally directed end of the L coupling 18 is connected by a pipe section 21 to one side of a conventional form of air proportioning device or mixer 22, which has its other side connected by a gaseous fuel supply pipe 23. The proportioning effect of this device or mixer 22 is augmented by the additional air supply to be admitted to the fuel supply to the burner, when the ports 15 and 16 are open by the vertical adjustment of the burner part 11 relatively to the extension or nipple 17.

To assure of a most thorough commingling of the air and gas, which is necessary for proper and efficient combustion at the burner, a baffle 24 is positioned in the extension or nipple 17, and the same is preferably made up from a length of coiled spring wire, the coil being preferably of tapered form and arranged with its larger end uppermost and of a diameter to snugly fit the bore thereof in a manner to sustain the baffle in centered position. The lowermost of the smaller convolutions of the baffle 24 may be formed to merge into a single lower and larger convolution 25, of equal diameter to that of the largest convolution at the upper end of the baffle, to give additional support to the device.

The baffle 24 is preferably of a length only slightly less than that of the extension or nipple 17 within which it is housed, and thus presents a number of convolutions of progressively increasing diameter upwardly thereof, in a direction of flow of fuel therethrough so that the fuel passing from the mixer 22 strikes these convolutions in a manner to be thoroughly remixed before reaching the burner. The ports 16, at the opposite sides of the extension or nipple 17, are positioned therein to discharge the additional air supply, admitted through the same directly into the path of the initially formed fuel supply and in a plane medially of the baffle 24, so that it in turn is thoroughly admixed in the remaining distance of upward travel of the fuel through the baffle or extension or nipple to the burner.

In use, the burner will be ignited at the opening 12, with the tubular portion 11 in its lowermost position to close the ports 15 and 16, thus the richer fuel mixed directly from the mixer 22 will be employed at the start of the operation of the burner. Now, as the burner heats up, the screw 19 will be adjusted to raise the burner 10 and tubular portion 11 and thereby open the ports 15

and 16, when the initial fuel supply will be diluted with the additional air supply admitted therethrough. A control valve (not shown) will, of course, be provided to regulate the gaseous fuel supply admitted through the supply pipe 23, so that with the burner in full operation the amount of the gas may be reduced to a minimum correspondingly with the increased air dilution of the initial fuel mixer at the ports 15 and 16.

As an instance of the use of the burner, as thus constructed and arranged, and in addition to its employment for more general heating purposes, the same may be housed within an enclosed structure, somewhat after the manner as shown in Figure 4. This structure may be employed as a radiator to be installed in the wall or floor of a room, and it consists of a casing 26, preferably of metal and of rectangular form. The upper side of the casing 26 is preferably open and the bottom wall thereof provided with a pair of parallel slotted openings 27, the latter forming air inlets. These openings or slots 27 are formed, in this instance, by the striking upwardly from the bottom wall of a pair of parallel flange portions 28, and supported on the upper edges of these flanges 28 is a second bottom wall 29, so that an air space is formed below the same. The inner surface of the opposite end and side walls of the casing 26 and the upper side of the inner bottom wall 29, are lined with a refractory material, such as fire brick or the like 30, and a central air inlet opening 31 is provided in the wall 29 and the lining 30, immediately below the position of the mixing device 22 to which the burner 10 is connected.

The upper side of the casing 26 is provided with a removable cover frame 32 which will preferably have a transparent wall portion 33 mounted within the opening of the frame, whereby the operation of the burner may be observed. To evacuate fuel gases from the interior of the casing 26 which gases may accumulate therein during the operation of the burner, suitable outlets 34 will be provided in one of the end walls just below the top edge therein and these outlets will be exteriorly piped to a common discharge pipe 35 leading to the atmosphere.

In the use of this type of radiator, the casing 26 will be set in the floor or wall of a room, preferably flush therewith, with suitable air and gaseous fuel connections leading to the same for the proper operation of the burner, and the casing will preferably be filled with a refractory material which acts to retain the heat, and when fully heated, permits of the reducing of the fuel consumption at the burner to a minimum. The refractory material to be so employed will preferably be in the form of broken up parts of hard burned bricks or the like. By employing broken brick within the casing and packing

it about and over the burner, the same will tend to absorb moisture from the atmosphere through condensation, so that the heat from the burner will be intensified thereby with a minimum of fuel consumption.

As has been hereinbefore suggested, the burner may be installed in any type of standard or special form of a heating furnace, stoves or the like, which ordinarily employ coal or other solid fuels for the heating thereof, in which case the particular form of casing herein described for housing the same will be eliminated. The burner may also be employed in conjunction with fireplace heaters or logs.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

25 A gas burner comprising a body, a hollow extension depending from the lower side of said body, a hollow member adapted to be telescopically engaged by said extension and to be connected to a fuel supply line, said extension and said member having ports in the same opening to the atmosphere when in registry, lugs within said extension, and screw means passed downwardly through said body and said lugs and having the lower ends 30 thereof bearing against the upper end of said hollow member for adjusting said extension relative to said member whereby to move the said ports into and out of registry for controlling an air supply to be admitted therefrom to the said extension for the dilution 35 of the fuel passing therethrough to the burner body.

CHARLES HERMAN PASCHKE.
